(57) **CLAIM**

The ornamental design for a sealing ring, shown and described.

DESCRIPTION

FIG. 1 is a perspective view of a first sealing ring showing our new design;

FIG. 2 is a top plan view thereof;

FIG. 3 is a bottom plan view thereof;

FIG. 4 is a front view thereof;

FIG. 5 is a rear view thereof;

FIG. 6 is a right side view of thereof, a left side view being identical thereto;

FIG. 7 is an enlarged perspective view, observed from above thereof;

FIG. 8 is an enlarged plane view, observed from above thereof;

FIG. 9 is an enlarged cross-section view taken along the line 9-9 of FIG. 8 thereof;

FIG. 10 is a perspective view of a second sealing ring showing our new design;

FIG. 11 is a top plan view thereof;

FIG. 12 is a bottom plan view thereof;

FIG. 13 is a front view thereof;

FIG. 14 is a rear view thereof;

FIG. 15 is a right side view thereof, a left side view being identical thereto;

FIG. 16 is an enlarged perspective view, observed from above thereof;

FIG. 17 is an enlarged plane view, observed from above thereof; and,

FIG. 18 is an enlarged cross-section view taken along the line 18-18 of FIG. 17 thereof.

The particular cross-hatching patterns in FIGS. 9 and 18 do not represent any particular materials.

The environmental structures shown in FIGS. 1-6 and 10-15 depict unclaimed environmental subject matter.
